ACCELERATION AND DECELERATION
CONTROLLER

Joseph C. McCune, Edgewood, Pa., assignor to
The Westinghouse Air Brake Company, Wil-
merding, Pa., a corporation of Pennsylvania

Application February 24, 1934, Serial No. 712,732

8 Claims. (Cl. 172—179)

This invention relates to acceleration and deceleration controllers, and more particularly to means for controlling the acceleration and deceleration of railway vehicles and trains.

In the operation of modern traction and interurban railway systems, the time required to accelerate and decelerate the vehicle or train becomes an important factor in maintaining fast schedules. In order to minimize the time required for acceleration and deceleration, and to make starts and stops more uniformly, it has been proposed to provide means for automatically controlling the acceleration and deceleration, so that such will not be dependent upon the skill of the operator.

It is a principal object of my invention to provide means for controlling both the acceleration and deceleration of a railway vehicle or train, which means will operate to control the maximum rate of acceleration or deceleration so as to prevent sliding of the wheels.

Another object of my invention is to provide an apparatus having a member responsive to changes in the rate of speed and providing for a desired maximum rate of acceleration and a desired maximum rate of deceleration, regardless of whether or not the vehicle or train is lightly loaded or heavily loaded.

Further objects of my invention will be apparent from the following description, which is taken in connection with the attached drawing illustrating one embodiment thereof, wherein the single figure there shown illustrates in diagrammatic form an inertia operated device and connected apparatus for controlling both the acceleration and deceleration of a vehicle or train.

As shown, the inertia operated device comprises a pendulum, 10 adapted to swing about a pivot 12 and having a body portion 14 carrying contacts 16 and 18 insulated therefrom. The contact 16 is adapted to engage resilient and yieldable, stationary contacts 20 and 22, while the contact 18 is adapted to engage similar contacts 24 and 26.

The contacts 16, 20 and 22 are adapted to control operation of the acceleration control apparatus, which I have shown in connection with a single vehicle motor having an armature 28 and a series field 30, although it will be readily apparent that any other number of motors may be used. The motor field and armature are adapted to receive current from a source through a trolley 32 and a ground connection 34. The flow of current to the motor is regulated by a controller having a resistance unit 36 adapted to

be varied by a rotatable drum 38 driven by a motor 40 through a worm and worm gear 42.

The motor 40 is preferably of the constant speed type, and may be energized from any suitable source through conductors 44. For controlling operation of the motor 40 there is provided a relay 46 having contacts 48 connected in the circuit to the motor. The contacts 48 remain closed so long as relay 46 is either deenergized or insufficiently energized to open the contacts.

The relay 46 is connected across a resistance device 50 in series with the vehicle motor and is, therefore, adapted to be energized in accordance with the flow of current to the motor.

Another resistance device 52 is connected in series with the relay 46, and has one terminal thereof connected to the aforementioned contact 20 and the other terminal thereof connected to the aforementioned contact 22.

It will thus be seen that when the pendulum 10 swings to the left, contact 16 will engage and bridge the two contacts 20 and 22, and thereby shunt the resistance device 52. The purpose of this will more fully hereinafter appear.

The contacts 18, 24 and 26 are, as is shown, adapted to control apparatus for controlling operation of the brakes.

For purposes of illustration, I have shown this apparatus as comprising a brake controlling valve device 54, and a brake valve device 56, for controlling the supply of fluid under pressure to a brake cylinder 58.

The brake valve controlling device 54 comprises a supply magnet valve section 60, a release magnet valve section 62, an inshot valve section 64, and a safety valve device 66 secured to the inshot valve section 64.

The supply magnet valve section 60 comprises a casing provided with a valve chamber 68, having constant communication with the brake cylinder 58 by passage 70 and pipe 72, and having disposed therein a double beat valve 74 secured to a valve stem 76. The double beat valve 74 is urged toward an upper seat 78 by a spring 80 acting upon a plunger 82 in engagement with the valve stem 76, so that when the valve is against the upper seat, fluid under pressure may flow from a reservoir 84 through the brake valve device 56, pipe 86, passage 88, past an open lower seat 88 to the valve chamber 68, and from thence to the brake cylinder 58 through passage 70 and pipe 72.

The double beat valve is urged to its lower seat 88 by an electromagnet in the upper portion of the casing, which when energized forces a

plunger 90 downwardly to urge the double beat valve to its lower seated position, and thereby cut off the supply of fluid under pressure to the brake cylinder.

5 The release magnet valve section 62 comprises a casing defining a valve chamber 92, having constant communication with the brake cylinder by way of passage 94 and pipe 72, and having disposed therein a valve 96 which cooperates with 10 a seat 98 to control the release of fluid pressure from the brake cylinder to the atmosphere, by way of a chamber 100, passage 102 and the safety valve device 66.

The valve 96 is urged toward seated position 15 by a spring 104, and to unseated position by an electromagnet in the upper part of the casing which, when energized moves a plunger 106 downwardly into engagement with the valve stem to unseat the valve.

20 The inshot valve section 64 comprises a casing defining a valve chamber 108 having communication with the reservoir 84 by way of passage 110, pipe 86 and brake valve device 56. Disposed in the valve chamber 108 is a ball valve 112, which 25 is engaged by a stem 114 associated with a piston 116 operatively mounted in a chamber 118, having constant communication with the atmosphere by way of a passage 120.

The ball valve 112 is urged to unseated position by a spring 122 acting to urge the piston 116 upwardly against stops 124, and when in unseated position fluid under pressure may flow from the chamber 108, and the reservoir 84, to the brake cylinder by way of passage 126 and 35 pipe 72. The purpose of the inshot valve section will hereinafter more fully appear.

40 The safety valve device 66 is preferably of the type commonly used in connection with fluid pressure brake equipment, and it is, therefore, considered unnecessary to describe this device in detail.

45 In a like manner the brake valve device 56 may be of any of the usual types, as for example, a rotary type having the usual release, application and lap positions and it is, therefore, not considered necessary to describe in detail this device.

The electromagnet controlling operation of the double beat valve 74 in the supply magnet valve section 60 has one terminal thereof connected to the aforementioned contact 24, while the electromagnet controlling operation of the release valve 96 in the release magnet valve section 62 has one terminal thereof connected to the aforementioned contact 26.

55 The contact 18 carried by the pendulum 10 is connected to a source of current supply, as for example, a battery 126, which has its other terminal connected to the remaining terminal of each of the aforementioned electromagnets.

60 It will thus be apparent that when the pendulum 10 swings to the right, and its contact 18 engages the contact 24, the electromagnet controlling operation of the supply valve 74 will be energized, and when the contact 18 engages the 65 contact 26 the electromagnet controlling operation of the release valve 96 will be energized. The purpose of this will appear presently.

70 In describing now the operation of the embodiment of my invention shown, it will be assumed that a vehicle or train equipped therewith is traveling on a level trackway, but it will, of course, be appreciated that successful operation of this or any other embodiment of the invention will be similar on either downhill or uphill grades.

75 When it is desired to accelerate a vehicle from

rest, the control motor 40 of the acceleration control apparatus is connected to a suitable source of supply, as by the closing of a switch. This motor will then cause rotation of the drum 38 at a speed which is predetermined by the speed of 5 the motor 40 and the relation of the worm and worm gear 42.

The first movement of the drum 38 connects the motor armature 28 and series field 30 to the source of current supply, with all of the resistance 10 unit 36 in series therewith. With the vehicle motor thus energized it will produce acceleration of the vehicle in accordance with the current supplied thereto.

If the vehicle is heavily loaded the vehicle motor 15 will require greater current to produce a given rate of acceleration than when lightly loaded. The control motor 40 is designed to drive the drum 38 at a rate which will cause current to be supplied to the vehicle motor at a rate which will 20 cause the motor to accelerate the vehicle at a desired maximum rate when heavily loaded. The increased adhesion between vehicle wheels and rails due to the load in the vehicle will permit this.

The relay 46 is designed to open contacts 48 25 and hold them open so long as current above a predetermined value flows in the relay winding. This current is of course proportional to the current supplied to the vehicle motor, and, as will be seen presently, may correspond to a value of vehicle motor current which causes the motor to exceed the desired maximum rate of acceleration, or to excessive overload current.

30 With the resistance device 52 in series with the relay 46 the vehicle motor current which produces 35 the desired maximum rate of acceleration will not cause the relay to open its contacts. But when the desired maximum rate of acceleration has been exceeded, the pendulum 10 has swung far enough to the left to cause its contact 16 to bridge contacts 20 and 22. This shunts the resistance device 52 and the increased current which immediately flows in the relay winding is sufficient to cause opening of contacts 48.

40 Were the resistance device 52 omitted, the relay would still be energized when contacts 20 and 22 are bridged. But by providing the resistance device 52 in the manner shown the relay will open its contacts 48 before contacts 20 and 22 are bridged when the motor current greatly exceeds 50 the normal maximum full load current, as when the brakes are dragging on the wheels during acceleration, or for other reasons. This then prevents overheating of the driving motor.

45 Opening of contacts 48 interrupts the circuit 55 to the control motor 40 and rotation of the drum 38 is thus arrested until the overload current diminishes below a chosen value, or the rate of acceleration diminishes to or below the desired value, as the case may be. When the rate of acceleration is the controlling factor, contacts 48 remain open until pendulum 10 swings to the right and contact 16 no longer bridges the contacts 20 and 22. The resistance device 52 is then again placed in series with relay 46, and the current decrease thus caused in the relay winding permits contacts 48 to again close, again energizing the control motor 40 to again rotate the drum 38.

70 If the vehicle is lightly loaded the operation is the same, but since a lower vehicle motor current will produce the desired maximum rate of acceleration, a lower current flows in the relay winding. However, the resistance of the resistance device 52 is such that as soon as the pendu- 75

lum 10 causes shunting of the resistance device, sufficient current flows in the relay winding to cause opening of contacts 48. The rotation of the drum 38 is thus arrested before the current supplied to the vehicle motor reaches a value which would cause sliding of the wheels, which would now occur at lower motor currents, due to the lightly loaded vehicle producing less adhesion between wheels and rails.

10 It will thus be seen that the inertia operated device so controls the operation of the relay 46 as to cause the vehicle to be accelerated at a desired maximum rate, regardless of the loading of the vehicle.

15 When it is desired to effect an application of the brakes to decelerate the vehicle, the handle of the brake valve device 56 is moved to application position, whereupon fluid under pressure flows from the reservoir 84 to the brake cylinder by way of pipe 86, passage 110, past the unseated ball valve 112, and through passage 126 and pipe 72.

20 At the same time, fluid under pressure will also flow to the brake cylinder through pipe 86, passage 88, past the open lower seat 89 of the supply valve 74, and through passage 10 and pipe 72. The supply of fluid to the brake cylinder will, therefore, be effected at a maximum rate.

25 When the fluid pressure in the brake cylinder has built up to a predetermined or chosen value, it will act upon the piston 116 to move it downwardly against resistance of the spring 122, until the ball valve 112 is seated. Fluid will thereafter flow to the brake cylinder only past the open lower seat 89 of the supply valve 74, and consequently at a lower rate. It will thus be seen that in effecting an application of the brakes fluid initially flows to the brake cylinder at a maximum rate, and immediately thereafter the inshot valve device acts to reduce the rate.

30 As the vehicle begins to decelerate with the application of the brakes, force of inertia will act upon the pendulum 10 to swing it to the right. When the contact 18 carried thereby engages stationary contact 24, the electromagnet controlling the supply valve 74 will be energized, thereby causing the supply valve to be moved to its lower seated position, and thus cutting off the supply of fluid under pressure to the brake cylinder.

35 If the rate of retardation is such as to also cause the contact 18 to engage the stationary contact 26, then the electromagnet controlling release valve 98 will be energized, and the release valve will be unseated to release fluid pressure from the brake cylinder to the atmosphere by way of the safety valve device 66.

40 In general, however, the pendulum will swing only far enough to the right to cause a cutting off of the supply of fluid to the brake cylinder, whereupon the supply will be lapped. Then as the vehicle continues to decelerate and the coefficient of friction between the rubbing parts of the brakes increases, so that the rate of retardation increases, the pendulum swings further to the right to effect a release of fluid pressure from the brake cylinder. The positioning of the contacts 24 and 26 with respect to the contact 18, therefore, determines the rate of retardation at which the cutting off and release of fluid occurs, regardless of the loaded condition of the vehicle.

45 If at any time the release of pressure from the brake cylinder causes the rate of retardation to decrease below that desired, then the pendulum

will swing far enough to the left to again admit fluid to the brake cylinder.

50 In normal operation, however, the pendulum usually moves first to cut off the supply of fluid to the brake cylinder, and thereafter swings with short movements back and forth to release pressure from the brake cylinder as the speed of the vehicle diminishes, as the tendency is for the rate of retardation to increase with decrease in speed, due to the constantly increasing coefficient of friction between the rubbing parts of the brakes.

55 As the vehicle nears a stop, the rate of retardation will tend to increase rapidly, due to the very rapid increase in coefficient of friction between the rubbing parts of the brake, but a smooth stop may be effected, since further control of the brakes may be effected by manipulation of the brake valve device 56.

60 The inertia operated device will, however, function to maintain a substantially constant rate of retardation, due to braking, throughout the entire deceleration period, and the brake valve device 56 need only be operated to initiate an application of the brakes, and to taper off the rate of retardation at the end of the deceleration period.

65 Since the inertia device operates according to the rate of retardation or rate of acceleration, it will be seen that I have provided an apparatus wherein a vehicle or train may be both accelerated and decelerated at desired rates, and starts and stops can, therefore, be made with greater uniformity and in a minimum length of time.

70 While one illustrative embodiment of the invention has been described in detail, it is not my intention to limit its scope to that embodiment or otherwise than by the terms of the appended claims.

75 Having now described my invention, what I claim as new and desire to secure by Letters Patent, is:

1. In a vehicle control apparatus, the combination with a driving motor, means for effecting progressive acceleration of the vehicle, and means responsive to current supplied to the vehicle motor for limiting the rate of acceleration, of means responsive to a rate of acceleration for controlling said second means.

2. Vehicle operating apparatus comprising a propulsion motor, a circuit for supplying current to said motor, a variable resistor and a fixed resistor in said circuit, means including a control motor for progressively varying said variable resistor, a control circuit for said control motor, a relay and a third resistor connected in series across said fixed resistor, said relay having contacts for controlling opening and closing of said control circuit, and means responsive to a chosen rate of acceleration of the vehicle for closing a shunt around said third resistor.

3. In a vehicle control apparatus, the combination with a driving motor, of means for controlling said motor to produce acceleration of the vehicle, a relay for controlling operation of said means, a circuit for supplying current to said relay, normally open contacts in said circuit, and an inertia operated device for closing said contacts.

4. In a vehicle control apparatus, the combination with a driving motor, of a circuit for supplying current to said motor, a variable resistor and a fixed resistor in said circuit, means including a control motor for progressively cutting out the resistance of said variable resistor, a relay for controlling said control motor, a circuit for connecting said relay to said fixed re-

sistor, normally open contacts in said circuit, and a pendulum device adapted to be operated according to the acceleration of the vehicle for closing said open contacts.

5. In a vehicle control system, in combination, a vehicle driving motor, means including a control motor for controlling the supply of current to said driving motor, electroresponsive means responsive to the current supplied to said driving motor for controlling operation of said control motor, and means governed by the rate of acceleration of the vehicle for controlling said electroresponsive means.

10 6. In a vehicle control system, in combination, a vehicle driving motor, acceleration apparatus having a control motor for controlling the supply of current to said driving motor, a relay responsive to the current supplied to said driving motor and operable when energized to a predetermined degree to control operation of said control motor, and means operated according to the rate of acceleration of the vehicle for controlling the degree of energization of said relay.

15 7. In a vehicle control apparatus, in combina-

tion, a driving motor, means for controlling the operation of said motor to produce a chosen rate of acceleration of the vehicle, a relay adapted when the energization thereof is abruptly changed by a predetermined amount to effect an operation of said last means to decrease the rate of acceleration, and means operated according to the rate of acceleration of the vehicle for controlling energization of said relay and operative to abruptly change the energization of 10 said relay by said predetermined amount at the instant the rate of acceleration exceeds said chosen rate.

15 8. In a motor control system, in combination, a motor for propelling a vehicle, a controller for controlling said propelling motor, a pilot motor for actuating said controller, a limit means responsive to the motor current, resistance means, and means responsive to the acceleration of the vehicle and cooperating with the limit means and the resistance means to control the operation of the pilot motor, thereby controlling the rate of acceleration of the vehicle.

JOSEPH C. McCUNE.
